RAILWAY-TRAFFIC-CONTROLLING APPARATUS.

Application filed February 4, 1923. Serial No. 6,718.

Our invention relates to railway traffic controlling apparatus, and particularly to apparatus of the type comprising train carried governing means controlled by energy received from the trackway.

We will describe two forms of apparatus embodying our invention, and will then point out the novel features thereof in claims.

10 In the accompanying drawings, Fig. 1 is a view, largely diagrammatic, showing one form of railway traffic controlling apparatus embodying our invention. Fig. 2 is a view showing a modified form of a portion of the 15 train carried apparatus illustrated in Fig. 1, and also embodying our invention.

Similar reference characters refer to similar parts in both views.

Referring first to Fig. 1, the reference 20 characters 1 and 1^a designate the track rails of a stretch of railway track over which traffic normally moves in the direction indicated by the arrow. These rails are divided, by means of insulated joints 2, into a 25 plurality of track sections, only one of which sections, A—D, is shown complete in the drawing. The track section A—D is provided with trackway apparatus for transmitting current to trains in the form of code 30 impulse combinations, which apparatus is here designated in general by the reference character Q. The impulse transmitting apparatus comprises a source of energy here shown as an alternator F, constantly connected with a motor E. The motor E is operatively connected with three circuit interrupting devices G, J and K all of which rotate at the same speed. Each of the 35 interrupting devices G, J and K comprises a flat disk of insulating material provided at its edge with contact plates 6. It will be seen from the drawing that disk G has one pair of oppositely disposed plates 6, that disk J has two pairs of similar contact 40 plates, and that disk K is provided with three sets of similar contact plates 6, the contact plates being circumferentially spaced about the edge of the disk, and that all the plates on each disk are connected together electrically. Each disk is provided with two oppositely disposed brushes 6^a adapted to be connected together when a pair of contact plates engages the two associated

brushes. A circuit controller 3 is controlled by traffic conditions in advance. When this 55 circuit controller is open no current is supplied to the rails; when contact 3—4^g is closed an impulse is delivered to the rails for each half revolution of device Q so that the trackway is then supplied with code impulse 60 combinations of one impulse each; when contact 3—4^j is closed the code impulse combinations supplied to the track rails each 65 comprise two impulses separated by a time interval. When contact 3—4^k is closed the code impulse combinations in the trackway each comprise three spaced impulses. As 70 here shown, the source F is an alternator, and it is, of course, apparent that each impulse impressed across the rails is in reality made up of a series of alternating current 75 impulses or cycles, but for purposes of this specification we will refer to each of these series as an impulse. It should be understood that alternating current for the code combinations is not essential to our invention.

The code impulse combinations thus supplied to the track, control train carried governing means through the medium of receiving apparatus located on a train which is shown diagrammatically at O. This receiving apparatus comprises two magnetizable cores 54 and 54^a located in advance of the forward axle 56 of the train and in inductive 80 relation with the two track rails 1 and 1^a, respectively. The cores 54 and 54^a are provided with windings 55 and 55^a, respectively, so connected that the voltages induced 85 therein by varying currents flowing in the opposite direction in the track rails at an instant are additive. The total voltage thus 90 created in the receiving windings 55 and 55^a is applied to the terminals of a relay N so that the relay is energized by each impulse 95 supplied to the trackway by apparatus Q. An amplifier 90 may be interposed between relay N and the receiving windings 55 and 55^a. The relay N controls a selector designated in general by the reference character 100 P. This selector comprises a contact device 17 in the form of a disk of insulating material, pivotally supported at its center 18 and provided at its periphery with two sets of teeth 21 and 22. A spring 19 constantly 105 urges the disk 17 in a counter-clockwise di-

- rection and the disk is therefore biased to the position in which it is illustrated, further motion in a counter-clockwise direction being prevented by a stop 20 which is engaged by one of the teeth 22. Rotation of the device 17 is controlled by an armature 13 pivoted at point 14. This armature is operated by a magnet 7 and is provided with a driving pawl 15 adapted to engage teeth 21. Disk 17 is further controlled by an armature 23 pivoted at point 24 and operated by a magnet 8. This armature is provided with a resilient arm 23^b carrying a latching pawl 23^a adapted to engage teeth 22. Magnets 7 and 8 are both normally de-energized, but are both energized when relay N becomes energized, that is, when an impulse is transmitted to the trackway by device Q. When magnet 7 is de-energized the armature 13 moves, under the influence of gravity, to the position shown in the drawing, in which position the pawl 15 is swung out of the path of the teeth 21. When magnet 7 becomes energized, the armature 13 is moved in a clockwise direction and the pawl 15 engages one of the teeth 21 and moves the disk 17 in clockwise direction, against the bias exerted by spring 19, by an amount equal to the pitch of one tooth 21.
- When magnet 8 is de-energized armature 23 occupies the illustrated position. When magnet 8 becomes energized, this armature is swung in a counter-clockwise direction so that the pawl 23^a engages one of the teeth 22 on disk 17, and if the disk has been moved away from its initial position by pawl 15 this engagement will prevent the disk from returning to such position. A bridging contact 25—26—27 of the usual form is operated by armature 23 and is arranged to be closed when the armature occupies an intermediate position, but to be open when the armature occupies either extreme position. The magnet 8 is so proportioned and constructed that a time interval elapses after the magnet is de-energized and before the armature 23 is released, which interval is longer than the time interval between successive impulses in a code impulse combination, but less than the time interval between successive combinations, in the current supplied to the trackway by the transmitting apparatus Q.
- This disk 17 carries at its edge three contact members 31, 32 and 33 electrically insulated from each other and adapted to cooperate with a fixed contact finger 34. The parts are so proportioned and disposed that as disk 17 is rotated in a counter-clockwise direction contact 34—31, 34—32, or 34—33 is closed according as the disk is rotated by a code combination of one, two or three impulses.
- Four slow releasing relays 9, 10, 11 and 12 are controlled by the contacts on disk 17.

These relays each have a time element greater than the time interval between successive code impulse combinations supplied by device Q.

Traffic governing apparatus, here illustrated as four signal lamps S, H, M and L, is controlled by the relays 9, 10, 11 and 12. The circuit for relay 12 may be traced from one terminal B of a suitable source of energy, not shown in the drawing, through wires 28 and 29, winding of relay 12, wire 30, contact 31—34 of device P, wire 35, contact 25—26—27 operated by armature 23, wire 36, winding of relay 9, and wire 37 to terminal C of the same source. When this circuit is closed relays 12 and 9 both become energized and current flows from terminal B, through wires 41 and 42, front contact 43 of relay 12, wire 44, lamp L, wire 45, front contact 46 of relay 9, to terminal C, and lamp L is lighted.

Another circuit may be traced from terminal B, through wires 28 and 38, winding of relay 11, wire 39, contact 32—34 of device P, wire 35, contact 25—26—27 operated by armature 23, wire 36, winding of relay 9, and wire 37 to terminal C. When this circuit is closed relays 9 and 11 are energized. Current then flows from terminal B, through wires 41 and 47, front contact 48 of relay 11, wire 49, lamp M, wires 45^a and 45, front contact 46 of relay 9, to terminal C, thus lighting lamp M.

A third relay circuit may be traced from terminal B, through wire 28, winding of relay 10, wire 40, contact 33—34 of device P, wire 35, contact 25—26—27 operated by armature 23, wire 36, winding of relay 9, and wire 37 back to terminal C. When this circuit is closed relays 9 and 10 both become energized and current flows from terminal B, through wire 41, front contact 50 of relay 10, wire 51, lamp H, wires 45^b and 45, front contact 46 of relay 9, to terminal C, thus lighting lamp H. It will be observed that the circuit for each of the relays 10, 11 and 12 also includes relay 9, and that consequently, when any one of relays 10, 11 or 12 is energized, relay 9 will also be energized. When relay 9 is de-energized, however, current flows from terminal B, through wire 53, lamp S, wire 52, back contact 46 of relay 9, to terminal C, thereby lighting lamp S.

As shown in the drawing circuit controller 3 is open and therefore no voltage is being supplied to the rails of section A—D. Relay N on board the train is therefore continuously de-energized. Magnets 7 and 8 are both de-energized, and armatures 13 and 23 occupy the illustrated position. Disk 17 is therefore held in its initial position and contacts 31—34, 32—34 and 33—34 are all open. Relays 9, 10, 11 and 12 are all de-energized. As a result lamps L, M and H

120

125

130

are all extinguished, but lamp S is lighted to indicate "stop".

We will now assume that contact 3-4^a of device Q becomes closed. The section 5 A-D is then supplied with a single impulse code combination. Each such impulse energizes relay N which relay is, of course, de-energized during the time interval between impulses. The first closing of the front 10 contact 80 of relay N completes the circuits for magnets 7 and 8. Magnet 7 actuates armature 13 carrying the driving pawl 15 and rotates disk 17 in a clockwise direction against the bias exerted by spring 19. The 15 amount of this motion is such that contact 31-34 is closed. When relay N next becomes de-energized, magnet 7 is de-energized, and armature 13 returns to the position 20 illustrated in the drawing. The disk 17 does not return, however, to its initial position because pawl 23^a latches the disk against movement. This latching effect continues, due to the slow acting characteristics of magnet 8, for a fixed time interval after magnet 25 8 becomes de-energized due to the opening of N. But this time interval is, as has been explained, less than the time interval between successive impulses of the single impulse code combinations. At the expiration 30 of the time interval of magnet 8, then, the armature 23 releases, and in returning to its original position contact 25-26-27 is momentarily closed. Contact 31-34 is already closed, and relays 12 and 9 are therefore 35 energized, thereby extinguishing lamp S and lighting lamp L to indicate "proceed at low speed". When the armature 23 is fully released contact 25-26-27 opens and disk 17 returns to its initial position, breaking contact 31-34, but relays 12 and 9, being slow releasing, hold their front contacts closed and lamp L continues to be lighted. The next impulse supplied to the trackway 40 by device Q causes relay N to again be energized, and the cycle of operations just described is repeated. The time interval between successive energizations of relays 12 and 9 is less than the release periods of these relays and therefore lamp L is continuously 45 lighted.

We will next assume that contact 3-4^a of device Q is closed. Code impulse combinations of two impulses each are then supplied to the trackway. The first impulse in each 55 such combination energizes relay N and actuates the apparatus as described before to close contact 31-34. During the comparatively short time interval after the termination of such first impulse and prior to the commencement of the second impulse in the same combination, pawl 15 releases, but pawl 23^a does not release. The second energization 60 of relay N will actuate pawl 15, as before, but since disk 17 has not returned to its initial position, the disk is moved fur-

ther in a clockwise direction so that contact 32-34 is closed. When relay N is next de-energized pawl 15 releases immediately but pawl 23^a holds for a time interval. During the return of armature 23 to its normal 70 position contact 25-26-27 is closed. The circuit is therefore completed for relays 9 and 11, which relays become energized. When pawl 23^a has fully released disk 17 returns to its initial position. The next 75 group of impulses repeats the same operation and relays 11 and 9 are again supplied with a surge of current. Since these relays are sufficiently slow acting to bridge the time interval between successive code 80 impulse combinations, lamp M is continuously lighted to indicate "proceed at medium speed".

Similarly, if contact 3-4^a of device Q is closed the trackway is supplied with code 85 impulse combinations, each such combination comprising three impulses. The operation of the apparatus when such combinations are supplied to the trackway will be readily understood from the foregoing, it 90 being sufficient here to say that for each code impulse combination, disk 17 is swung into a position in which contact 33-34 is closed. The release of armature 23 after each combination then completes the circuit for relays 9 and 10, and these relays, being slow 95 releasing, are continuously closed, and lamp H is lighted to indicate "proceed at high speed".

Finally, we will assume that uninterrupted alternating current is supplied to the trackway as by the sticking of device Q or because of some other abnormal condition. Relay N is therefore continuously energized. Magnets 7 and 8 then become continuously 100 energized. It will be seen that the operation of armature 13 by magnet 7 will advance disk 17 one tooth so that contact 31-34 is closed. Magnet 8 being energized, however, contact 25-26-27 operated thereby is open, and relays 12 and 9 are both de-energized. Relays 11 and 10 are also, of course, de-energized and a stop indication is therefore displayed by the lighting of lamp S. In similar manner a stop indication 110 would be displayed should relay N be continuously energized with disk 17 in such position as to close either contact 32-34 or 115 33-34.

The modified form of train carried apparatus illustrated in Fig. 2, is suitable for cooperation with the trackway apparatus shown in Fig. 1. That is to say, relay N is energized by code impulse combinations of one, two or three impulses in accordance with traffic conditions. Device P is replaced by a device P' comprising a disk 17 pivotally supported at point 18 and provided on its periphery with two spaced sets of teeth 21 and 22. A radially extending arm 65, the func- 120 125 130 135

tions of which will appear hereinafter, is rigidly fastened to disk 17. The disk is biased to an initial position, in which position it is illustrated in the drawing, by means of a 5 spring 19 which constantly urges the disk in a clockwise direction. Further motion of the disk in such direction is prevented by a fixed stop 66 which engages arm 65.

The motion of disk 17 is controlled by a 10 driving magnet 58, and by a latching magnet 57 which controls an escapement yoke T adapted to cooperate with the teeth 21 and 22. These magnets 58 and 57 are both supplied with energy over a front contact 80 of 15 relay N and so are energized when relay N is energized. A plunger 59 of magnetizable material is resiliently connected with arm 65 by means of a coil spring 67. When magnet 58 is energized plunger 59 is drawn downward, thus urging disk 17 in a counter-clockwise direction against the bias exerted by 20 spring 19. By means of a cylinder 60 of conducting material surrounding plunger 59, magnet 58 is made slow releasing so that 25 after this magnet is de-energized the driving torque exerted upon disk 17 through spring 67 continues for a time interval greater than the interval between successive impulses in the same code impulse combination, but less 30 than the time interval between successive combinations.

The escapement yoke T comprises a pair of oppositely disposed detents 62 and 63, disposed on opposite sides of the disk 35 17 and arranged to cooperate with teeth 22 and 21, respectively. The whole yoke is pivotally supported at point 61 and is provided with an armature 78 controlled by magnet 57. As shown in the 40 drawing magnet 57 is de-energized and armature 78 has dropped down onto a fixed stop 79 under the influence of gravity. In this position of the yoke T, detent 62 is out of the path of teeth 22. It will be observed 45 that the detent 63 is provided with a flexible finger 64 to prevent motion of the disk in a counter-clockwise direction, but to allow motion of such disk in the opposite direction, when the yoke is in the position illustrated 50 in the drawing.

The reference character R designates a contact mechanism controlled by the arm 65 on disk 17. This mechanism comprises a member 75 pivoted at point 76 and biased by 55 gravity to the position shown in the drawing, in which position the member rests upon a fixed stop 77. The member 75 is provided with three spaced insulated rigid contact fingers 69, 71 and 73, adapted to cooperate respectively with three flexible contact fingers 70, 72 and 74 which are electrically connected with the member 75, and therefore with each other. The end of arm 65 is provided with a flexible tongue 68 which engages the 60 fingers 70, 72 and 74 as disk 17 moves in a

counter-clockwise direction. The parts are so arranged that when arm 65 is swung downward the flexure of the tongue 68 and the contact fingers engaged thereby permit motion of the arm without disturbing the 70 position of the member 75, but when the arm 65 returns to its upper position member 75 is rotated upwardly about its pivot, as will appear more in detail hereinafter.

The signal lamps S, L, M and H are controlled by relays 9, 10, 11 and 12 in the same manner as already described in connection with Fig. 1.

As shown in the drawing, the parts are in the positions corresponding to the continuously de-energized condition of relay N. Under this condition magnets 57 and 58 are both de-energized. Armature 78 engages stop 79 so that detent 62 is disengaged from teeth 22, and disk 17 occupies its initial position under the influence of spring 19. In this position tongue 68 is above finger 70. All contacts of the contact mechanism R are open, and relays 9, 10, 11 and 12 are all de-energized. Lamp S is therefore energized 90 to indicate "stop".

We will now assume that relay N is supplied with code impulse combinations of one impulse each. When the relay N becomes energized the closing of its front contact 80 completes the circuits for magnets 57 and 58 which magnets thereupon become energized. The energization of magnet 58 draws plunger 59 downward and exerts upon disk 17, through spring 67, a 100 torque which urges the disk in a counter-clockwise direction against the bias of spring 19. At the same time the energization of magnet 57 raises armature 78 and rotates the yoke counter-clockwise about pivot 61. 105 During this motion the first tooth 21 is released, and disk 17 moves counter-clockwise the distance of one tooth, further motion in this direction being prevented by engagement of a tooth 22 with detent 62. During 110 this motion of disk 17, tongue 68 moves downwardly past finger 70, the resistance of the tongue and the finger permitting this motion, and tongue 68 now extends between fingers 70 and 72. At the end of the first 115 impulse relay N becomes de-energized, thereby de-energizing magnets 57 and 58. Magnet 57 immediately releases, allowing yoke T to return to its original position, but due to its slow acting characteristics plunger 59 is held down for a time interval. During 120 this interval disk 17 is held in place, the finger 64 of detent 63 engaging a tooth 21 and preventing further motion in a counter-clockwise direction. The time interval 125 during which plunger 59 is held down is, however, less than the time interval between successive code impulse combinations, and when plunger 59 is released by magnet 58, disk 17 returns to its initial position, the 130

135

flexure of finger 64 permitting the teeth 21 to pass in this direction. In returning to its initial position, tongue 68 engages finger 70 and due to the resistance offered by the tongue to downward flexure, finger 70 is bent upward to close contact 69-70. A circuit is then closed from terminal B, through wires 28 and 29, winding of relay 12, wire 30, contact 69-70, member 75, wire 36, winding of relay 9, and wire 37 back to terminal C. Relays 9 and 12 are therefore energized, lamp S is extinguished and lamp L is lighted. As the motion of disk 17 toward its initial position continues member 75 is swung upward until finger 70 is released by tongue 68, and the member 75 then drops back to its original position thereby opening contact 69-70. The motion of disk 17 is arrested by stop 66 engaging arm 65. When relay N receives the next impulse the same cycle of operations is performed. It follows that when relay N is receiving code impulse combinations of one impulse each, relays 12 and 9 receive a surge of energy for each such combination. But, due to the slow releasing characteristics of these relays, they hold their front contacts closed during the intervals between successive code impulse combinations and lamp L is constantly lighted.

We will next assume that relay N is receiving code impulse combinations of two impulses each. During the first impulse of each combination disk 17 is rotated in a counter-clockwise direction for a distance of one tooth as explained in connection with the single impulse combinations thus bringing tongue 68 between fingers 70 and 72. At the end of such first impulse the de-energization of magnet 57 allows yoke T to return to its original position to prevent the return of disk 17 as before, but before plunger 59 is released by magnet 58, relay N is energized by a second impulse. Magnets 57 and 58 therefore again become energized, the yoke T is again swung in a counter-clockwise direction and disk 17 is moved, by torque applied through spring 67, into a position wherein tongue 68 is between fingers 72 and 74. At the end of this second impulse, the opening of relay N de-energizes magnets 57 and 58, and yoke T returns to its original position. Disk 17 is now held by finger 64 against further motion by the torque exerted by plunger 59. At the expiration of the time interval required for the release of magnet 58, spring 19 moves disk 17 back to its initial position. During this motion tongue 68 engages finger 72 and closes contact 71-72. A circuit is then closed from terminal B, through wires 28 and 38, winding of relay 11, wire 39, contact 71-72, member 75, wire 36, winding of relay 9, and wire 37 back to terminal C. Relays 11 and 9 then become energized and lamp M is light-

ed. As the motion of disk 17 toward its initial position continues, member 75 is swung upwardly about its pivot until the tongue 68 moves out of the path of finger 72, whereupon contact 71-72 opens and member 75 drops back into the position in which it is illustrated in the drawing. The parts are so arranged that in thus returning to its original position, finger 70 does not engage tongue 68, and hence contact 69-70 does not become closed. The next group of impulses causes contact 71-72 to again become closed, and relays 11 and 9 are therefore energized once for each code impulse combination. Relays 11 and 9 being slow releasing, lamp M is continuously lighted as long as relay N receives the two impulse code combinations.

It will be plain from the foregoing that when relay N receives code impulse combinations of three impulses each, the operation of the apparatus will be similar to the operation just described in connection with the two impulse combinations with the exception that with the three impulse code combinations, disk 17 will be advanced 3 teeth during each combination and that when the disk returns to its initial position, contact 73-74 will be closed instead of contact 71-72. The closing of contact 73-74 completes a circuit from terminal B, through wire 28, winding of relay 10, wire 40, contact 73-74, member 75, wire 36, winding of relay 9, and wire 37 back to terminal C. It follows that relays 10 and 9 are energized once during each code impulse combination. Due to the slow releasing characteristics of these relays their front contacts will remain closed during the period between successive energizations, and lamp H will therefore remain lighted.

Should relay N be continuously energized, as by the presence of uninterrupted alternating current in the trackway, magnets 57 and 58 both would be continuously energized, but all contacts on mechanism R would be open and a stop indication would be displayed.

It will be seen that while our invention embodies the use of timing means, the actual selection between code is accomplished by counting the number of impulses in each group and that wide variations in the various time intervals may be tolerated without interference with the proper operation of the apparatus.

It should also be pointed out that since the relay 9 is in each case energized in series with one of the relays 10, 11 or 12, it is plain that unless a high, medium or low speed indication is actually being displayed, the relay 9 will be de-energized, and the stop lamp S will be lighted.

Although we have herein shown and described only two forms of apparatus embodying our invention, it is understood that

various changes and modifications may be made therein within the scope of the appended claims without departing from the spirit and scope of our invention.

5 Having thus described our invention, what we claim is:

1. Railway traffic controlling apparatus comprising means in the trackway for supplying code impulse combinations to a train, 10 each combination comprising a different number of impulses, and train-carried governing means selectively responsive to the number of impulses in each combination.

2. Railway traffic controlling apparatus 15 comprising means in the trackway for supplying code impulse combinations to a train, means controlled by traffic conditions for varying the number of impulses in each combination, and train-carried governing mechanism selectively responsive to the number of impulses in said combinations.

3. Railway traffic controlling apparatus 25 comprising a stretch of railway track, means for supplying code impulse combinations to the track rails, each combination comprising a different number of impulses, and train-carried governing means controlled by energy received from the trackway and selectively responsive to the number of impulses in said combinations.

4. Railway traffic controlling apparatus 35 comprising a device biased to an initial position, a relay, means effective when said relay is energized to move said device a predetermined distance away from said initial position, means effective for a fixed interval of time after said relay is de-energized for holding said device against such bias, and means for supplying said relay with code 40 impulse combinations, the number of impulses in each combination depending upon traffic conditions.

5. Railway traffic controlling apparatus 45 comprising a device biased to an initial position, a relay, means effective when said relay is energized to move said device a predetermined distance away from said initial position, means effective for a fixed interval of time after said relay is de-energized for holding said device against such bias, means for supplying said relay with code impulse combinations, the number of impulses in each combination depending upon traffic conditions, and the time interval between successive impulses in a combination being smaller than said fixed interval of time, but the time interval between successive combinations being greater than said fixed interval of time.

6. Railway traffic controlling apparatus 60 comprising a device biased to an initial position, a relay, means effective when said relay is energized to move said device a predetermined distance away from said initial position, means effective for a fixed interval of time after said relay is de-energized for

holding said device against such bias, means for supplying said relay with code impulse combinations, the number of impulses in each combination depending upon traffic conditions, a slow acting relay, and means for energizing said slow acting relay when said device is moved out of its initial position. 70

7. Railway traffic controlling apparatus comprising a device biased to an initial position, a relay, means effective when said relay is energized to move said device a predetermined distance away from said initial position, means effective for a fixed interval of time after said relay is de-energized for holding said device against such bias, means 80 for supplying said relay with code impulse combinations, the number of impulses in each combination depending upon traffic conditions, a slow acting relay, means for energizing said slow acting relay when said device is moved out of its initial position, and governing means on the train controlled by said slow acting relay. 85

8. Railway traffic controlling apparatus comprising a train-carried relay, means for supplying said relay with code impulse combinations, means for varying the number of impulses in each combination in accordance with traffic conditions, and governing means controlled by said relay and selectively responsive to the number of impulses in each said combination. 95

9. Railway traffic controlling apparatus comprising a train-carried relay, means for supplying the relay with code impulse combinations, a device biased to an initial position, means for moving said device away from such position a predetermined amount for each energization of said relay, and governing means on the train controlled in accordance with the position of said device. 100 105

10. Railway traffic controlling apparatus comprising a train-carried relay, means for supplying the relay with code impulse combinations, a device biased to an initial position, means for moving said device away from such position a predetermined amount for each energization of said relay, means effective during the time interval between successive impulses in a combination to latch up said device, and governing means controlled in accordance with the position of said device. 110 115

11. Railway traffic controlling apparatus comprising a train-carried relay, means for supplying the relay with code impulse combinations, a device biased to an initial position, means for moving said device away from such position a predetermined amount for each energization of said relay, means effective during the time interval between successive impulses in a combination to latch up said device, a slow acting relay controlled in accordance with the position of said device and having a time period greater than 120 125 130

- the time interval between successive combinations, and governing means controlled by said slow acting relay.
12. Railway traffic controlling apparatus comprising a train-carried device biased to an initial position, means for supplying the trackway with code impulse combinations, means for varying the number of impulses in each combination in accordance with traffic conditions, a driving pawl on the train arranged to move said device a predetermined distance away from its initial position for each impulse and a latching pawl for latching said device during the time interval between impulses in a combination but not during the time interval between successive combinations.
13. Railway traffic controlling apparatus comprising means for supplying the trackway with code impulse combinations, means for varying the number of impulses in each combination in accordance with traffic conditions, a plurality of contacts on the train, means for selectively operating said contacts in accordance with the number of impulses in each combination being supplied to the trackway, and governing means controlled by said contacts.
14. Railway traffic controlling apparatus comprising means for supplying the trackway with code impulse combinations, means for varying the number of impulses in each combination in accordance with traffic conditions, a plurality of contacts on the train, means for selectively operating said contacts in accordance with the number of impulses in each combination being supplied to the trackway, and a plurality of governing means one controlled by each of said contacts.
15. Railway traffic controlling apparatus comprising means for supplying the trackway with code impulse combinations, means for varying the number of impulses in each combination in accordance with traffic conditions, a plurality of contacts on the train, means for selectively operating said contacts in accordance with the number of impulses in each combination being supplied to the trackway, a plurality of relays one controlled by each said contact, and governing means controlled by said relays.
16. Railway traffic controlling apparatus comprising a train-carried device biased to an initial position, means for supplying the trackway with code impulse combinations, means for varying the number of impulses in each combination in accordance with traffic conditions, a driving pawl on the train arranged to move said device a predetermined distance away from its initial position for each impulse supplied to the trackway, a latching pawl for latching said device during the time interval between impulses in a combination but not during the time interval between successive combinations, and governing means controlled by said device.
17. Railway traffic controlling apparatus comprising a train-carried device biased to an initial position, means for supplying the trackway with code impulse combinations, means for varying the number of impulses in each combination in accordance with traffic conditions, a driving pawl on the train arranged to move said device a predetermined distance away from its initial position for each impulse supplied to the trackway, a latching pawl for latching said device during the time interval between impulses in a combination but not during the time interval between successive combinations, and governing means controlled by said device and by said holding pawl.
18. Railway traffic controlling apparatus comprising means for supplying the trackway with code impulse combinations, a device on a train biased to an initial position, a relay on the train arranged to be energized by each said impulse, driving mechanism effective when said relay is energized to advance said device a predetermined distance away from such initial position, latching mechanism effective after energization of said relay for a time interval greater than the interval between impulses in the same combination to prevent the return of said device to its initial position, a plurality of contacts arranged to be successively closed as said device is moved away from its initial position, and governing means controlled by said contacts and including slow acting means having a time interval greater than the time interval between successive combinations.
19. Railway traffic controlling apparatus comprising means for supplying the trackway with code impulse combinations, a device on a train biased to an initial position, a relay on the train arranged to be energized by each said impulse, driving mechanism effective when said relay is energized to advance said device a predetermined distance away from such initial position, latching mechanism effective after energization of said relay for a time interval greater than the interval between impulses in the same combination to prevent the return of said device to its initial position, a plurality of contacts arranged to be successively closed as said device is moved away from its initial position, and governing means controlled by said contacts and by said latching mechanism.
20. Railway traffic controlling apparatus comprising means for supplying the trackway with code impulse combinations, a device on a train biased to an initial position, a train-carried relay adapted to be energized by each said impulse, means effective after energization of said relay for a time interval

greater than the time interval between successive impulses in a combination to apply a force to said device in a direction opposite to said bias, an escapement for releasing said device for limited movement by said force when said relay is energized, and governing means responsive to the position of said device.

21. Railway traffic controlling apparatus comprising means for supplying the track-way with code impulse combinations, means for varying the number of impulses in each combination in accordance with traffic conditions, a device biased to an initial position, a train-carried relay arranged to be energized by each said impulse, means for applying to said device each time said relay is energized a force tending to move the device against said bias, an escapement normally preventing movement of said device by said force, means for actuating said escapement when said relay is energized to allow movement of the device for a predetermined distance, the device being arranged to return to its initial position during the time interval between successive combinations, a contact arranged to be closed as the device returns to its initial position, and governing means controlled by said contact.

22. Railway traffic controlling apparatus comprising a train-carried relay, means for supplying the relay with code impulse combinations, a device biased to an initial position, means for moving said device away from such position a predetermined amount for each energization of said relay, a contact arranged to be closed when said device is returning to said initial position, a slow acting relay controlled by said contact, and governing means controlled by said slow acting relay.

23. Railway traffic controlling apparatus comprising a train-carried relay, means for supplying the relay with code impulse combinations, a device biased to an initial position, means for moving said device away from such position a predetermined amount for each energization of said relay, a plurality of controlling contacts selectively operated depending upon the position of said device, a bridging contact arranged to be closed when said device is returning to said initial position, a plurality of slow acting relays each controlled by an associated one of said controlling contacts all said relays being controlled by said bridging contact, and governing means controlled by said slow acting relays.

24. Railway traffic controlling apparatus comprising a train-carried relay, means for

supplying the relay with code impulse combinations, a device biased to an initial position, means for moving said device away from such position a predetermined amount for each energization of said relay, a first contact controlled by the position of said device, a second contact arranged to be closed only when said device is returning to said initial position, a slow acting relay controlled by said two contacts, and governing means controlled by said slow acting relay.

25. Railway traffic controlling apparatus comprising a train-carried relay, means for supplying the relay with code impulse combinations, a device biased to an initial position, means for moving said device away from such position a predetermined amount for each energization of said relay, means effective during the time interval between successive impulses in a combination to latch up said device, a contact arranged to be closed for a brief interval after such latching means becomes ineffective, a slow acting relay controlled by said contact, and governing means controlled by said slow acting means.

26. In a continuous indication train control system, in combination, a translating device on the train, means controlled by traffic conditions for transmitting electrical impulses through said translating device, step-by-step mechanism controlled by said translating device operating through a certain number of steps and then returning to initial position continually so long as impulses are transmitted through said translating device, and indication means controlled by said mechanism and held at one indication only so long as said mechanism completes its phase of operation in predetermined intervals.

27. In a continuous indication train control system, in combination, a track, a vehicle travelling thereon, a translating device on the vehicle, means controlled by traffic conditions for transmitting electrical impulses through said translating device, a member on the vehicle moved to an initial position upon the reception of each impulse, constantly acting means for moving said member away from initial position at a predetermined rate, a train control magnet, and means for closing a circuit therethrough upon the reception of each impulse only if said member has reached a certain position.

In testimony whereof we affix our signatures.

LARS O. GRONDAHL.
